UNITED STATES PATENT OFFICE.

LADISLAUS DE DOORY, OF BOSTON, MASSACHUSETTS, ASSIGNOR TO AUTO BILL POST INC., OF BOSTON, MASSACHUSETTS, A CORPORATION OF MASSACHUSETTS.

DESIGN FOR AN ADVERTISING-AUTOMOBILE.

51,634.

Specification for Design.

Patented Jan. 1, 1918.

Application filed October 11, 1916. Serial No. 125,122. Term of patent 3½ years.

To all whom it may concern:

Be it known that I, LADISLAUS DE DOORY, a subject of the King of Hungary, but now residing at Boston, in the county of Suffolk and State of Massachusetts, have invented a certain new, original, and ornamental Design for an Advertising-Automobile, of which the following is a specification, reference being had to the accompanying drawings, forming part thereof, in which—

Figure 1, is a side elevational view of the advertising automobile, showing one of the oblong side and end panels of the vehicle.

Fig. 2, is a view, showing the three-part end panels of the vehicle; and

Fig. 3, is a top or plan view of the advertising automobile as structurally embodying my new design.

I claim:—

The ornamental design for an advertising automobile, substantially as shown and described.

LADISLAUS DE DOORY.
